UNITED STATES PATENT OFFICE

MAXIMILIAN SCHNEFEL, OF NEWARK, NEW JERSEY, ASSIGNOR TO SCHNEFEL BROTHERS, INC., A CORPORATION OF NEW JERSEY

PENCIL FINGER NAIL CLEANER

Application filed April 2, 1931. Serial No. 527,337.

This invention relates to finger nail cleaners or whiteners, and belong to that type of implements for the treatment of the finger nails whereof the body of the article has the 5 form of a pencil sharpened at one end.

It is the object of this invention to provide a pencil form body made up of partly rounded members secured together, and having arranged lengthwise within the body and on 10 one side of the axial line thereof a core of material for application to the nails, whereby when the pencil body is sharpened at one end the substance of the body and the material of the core will both extend to the point of the 15 body. It is not intended to limit this invention in any manner to the substance of which the body of the pencil is made, or to the character of the core with respect to the ingredients mixed to constitute the core.

20 In the accompanying drawings the parts of this invention and the preferred combinations thereof are illustrated, and Fig. 1 shows a side view with the substance of the body extending to the point which may be fashioned at one end of the body. For clearness the scale of drawing is twice the usual size.

25 Fig. 2 represents the parts illustrated in Fig. 1 turned one-half way around and showing a side view with the material of the core 30 extending to the point of the pencil.

Fig. 3 is a side view of all parts assembled showing both body and core extending to the point.

35 Fig. 4 is a flat side view of one of the half round members of which the body of the pencil is composed, showing the core extending lengthwise therein and arranged on one side of the axial center line of the member.

Fig. 5 is a cross section of the parts as- 40 sembled.

Throughout the drawings and description the same numeral is used to refer to the same part.

Considering the drawings, the half round 45 members 1 and 2 may be of wood or other suitable substance, secured together on the longitudinal line 3. In Fig. 1 the body is shown having one end 4 cut into a point and the substance of the body extending 50 to the point. In Fig. 2 the substance of the

body has the conical end 5, but the end of the point is composed of the sharpened end 6 of the core 7.

In Fig. 4 it is shown that the core 7 extends lengthwise of the body and is let into the flat side of each of the half round members 1 and 2, as is best set forth in Fig. 5. The core is arranged at one side of the axial center line of the body.

In the operation of this invention if the 60 pencil body be sharpened as a lead pencil is sharpened at one end, the substance of the wooden body will extend to the point 4, and may be applied to the cuticle at the base of the nails. Also the core will be exposed on 65 one side, and it may be of red material as illustrated for cleaning and polishing the finger nails. Thus either the point of the body or the exposed end portion of the core 70 may be applied to the treatment of the 70 finger nails in the customary manner.

Having now described this invention and the manner of its use, I claim:—

1. A pencil having a core composed of ma- 75 terial for the treatment of finger nails, the body of said pencil being formed of wood, and the point of the pencil being sharpened whereby a portion of the wooden body at the end thereof is sharpened and extends to the exposed end of the core on one side of the 80 core, the point of the pencil consisting of a portion of the body and a portion of said core.

2. A pencil having a core composed of ma- 85 terial for the treatment of finger nails, the body of said pencil being formed of wood, the said core of the pencil being arranged lengthwise to one side of the axial line of the body, and the point of the pencil being sharpened whereby a portion of the wooden body extends to the exposed end of the core 90 on one side of the core.

In testimony whereof I affix my signature.

MAXIMILIAN SCHNEFEL.
